(57) **CLAIM**

The ornamental design for a cosmetics holder, as shown and described.

DESCRIPTION

FIG. 1 is a top perspective view of a cosmetics holder, showing my new design;

FIG. 2 is a bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof; and,

FIG. 9 is an exploded front perspective view thereof.

The dot-dash broken lines of FIG. 9 is included to show relationship of cap, body, and base cylinders only and form no part of the claimed design.
